UNITED STATES PATENT OFFICE.

PILADE BARBUCCI, OF NAPLES, ITALY.

DRYING PLANT.

1,344,163.

Specification of Letters Patent. Patented June 22, 1920.

Application filed March 22, 1919. Serial No. 284,440.

To all whom it may concern:

Be it known that I, PILADE BARBUCCI, subject of the King of Italy, and resident of Naples, Italy, have invented certain new and useful Improvements in Plants for Drying Materials Arranged on Frames, of which the following is a specification.

This invention relates to plants for drying materials arranged on frames or other supporting means and has for its object to provide an arrangement comprising ventilating means reciprocating in the room or chamber along the series of frames on which the material to be dried is arranged, and adapted to produce a uniform air circulation between said frames and in the longitudinal direction with regard to the series of said frames by generating air streams the intensity of which changes in a continuous manner from a minimum to a maximum and vice-versa; further the direction of said air streams may be periodically reversed.

In the annexed drawing:

Figure 1 shows diagrammatically a complete drying plant according to the invention in longitudinal section;

Fig. 2 is a plan view of the same;

Fig. 3 is a transverse section on line $x-x$, Fig. 2, and

Fig. 4 shows in an enlarged scale the ventilating apparatus in plan.

As shown in Figs. 1 to 3, in the room 1, which may be a chamber, coffer, casing or the like, a number of frames 2 are arranged in one or two longitudinal series, said frames being superposed to each other and adapted to receive the material to be dried.

On the floor, in the space between the two series of frames 2, or, generally, along one of said series, is placed a track 3, on which runs the ventilating apparatus 4, provided with wheels 5, and driven in any suitable manner as, by way of example, by an electromotor 6, the operation of which is reversed at each end of the strokes of the apparatus 4, by means of a reversing lever cooperating with the members 13 and 14 secured to the end walls of the room or casing.

The apparatus 4 is formed by a casing 8 having a height corresponding with the total height of the frame ranges, in which casing are mounted one or more ventilating members as fans 9; the casing 8 is provided with at least one pair of openings in register with each ventilating member, one of them being

the inlet opening and the other the exhaust opening.

In the construction shown in the drawings, the casing 8 is provided with two exhaust openings 10, 10' and two inlet openings 11, 11', these openings being in the opposite walls of the casing 8, in front of the frame ranges.

The openings 10, 10', 11 and 11' which are provided at the same side of the casing, are formed by mouths the axes of which are preferably inclined in diverging directions and inclined with regard to the longitudinal axis of the frame series and with such an inclination, depending upon the length of the room, as to have the air streams utilized in their whole length.

Owing to the arrangement of the fans 9 shown on the drawing, that is with their axes perpendicular to the path of the apparatus 4, the air circulates in the direction of the arrows in Fig. 2, and two air streams E and F are produced which flow in opposite directions passing between the frames 2 of one series, while the air streams G, and H, directed toward the apparatus 4, pass between the frames of the opposite series. The same result may be attained by causing the openings 10 and 11 to operate as exhaust ones and the openings 10' and 11' as inlet ones or vice-versa, or further by using a single one of the openings 10, 10' and one of openings 11, 11' one of the two above mentioned openings operating in this case as inlet opening and the other as exhaust one.

The rotation of the fans 9 and thence the direction of air streams may be periodically reversed, by way of example, by means of the same lever 7 coöperating with the fixed members 13 and 14 in the manner above stated.

In any case, in a plant according to this invention a very strong air circulation is effected between the several frame ranges and the air streams are utilized in their whole length.

Further, as said streams have diverging directions, the material arranged on the frames is uniformly ventilated, also near the sides of said frames. The various portions of the room or chamber in which the frames are arranged are acted on by air streams in a thoroughly uniform manner, as the ventilating apparatus 4, owing to its continuous reciprocation in the chamber,

comes gradually at equal distances from the same.

Finally the material is subjected to air streams the intensity of which changes in a continuous manner from a minimum to a maximum and vice-versa, and therefore the temperature is different in the various zones of the room or chamber, as in any given zone the temperature is higher when the 10 ventilating apparatus is removed from the same and lower when said apparatus is near.

The plant is finally provided with exhausters 12 for discharging the ambient air.

What I claim as my invention and desire 15 to secure by United States Letters Patent is:

1. Apparatus for drying materials in a drying room, comprising, a plurality of supporting means arranged longitudinally in the room, and a ventilating device reciprocating along said supporting means and embodying a casing having openings in its walls facing said supporting means and ventilating means inside said casing.

2. Apparatus for drying materials in a 25 drying room, comprising a plurality of supporting means arranged longitudinally in the room, and a ventilating device recipro-

cating along said supporting means, and embodying a casing provided with mouths in its walls facing said supporting means 30 and ventilating means inside said casing, said mouths being inclined in diverging directions with respect to the path of said casing, and said ventilating means producing simultaneously draft air streams and blast 35 air streams between said supporting means.

3. Apparatus for drying materials in a drying room, comprising a plurality of supporting means arranged longitudinally in the room, a ventilating device embodying a 40 casing having mouths in its walls facing said supporting means and ventilating means located in said casing, and means for reciprocating said casing in said room along said supporting means, said ventilating 45 means producing simultaneously draft air streams and blast air streams between said supporting means.

Signed at Naples, Italy, this 25th day of Febry., A. D. 1919.

PILADE BARDUCCI.
